WIND-UP MECHANISM

Karl E. Anderson, Lakewood, Ohio, assignor to
The Dobeckmum Company, Cleveland, Ohio, a
corporation of Ohio

Application November 17, 1930
Serial No. 496,110

13 Claims. (Cl. 242—75)

This invention relates to wind-up mechanism and more particularly to means for supplying slip sheet or liner between convolutions of the wound or reeled material, and to speed compensating means for the mechanism.

The general object of the invention is to provide means for supplying slip sheet or liner between convolutions of the wound or reeled material in combination with automatic compensating means for controlling and maintaining the tension substantially uniform in the wound or reeled material and in the slip sheet or liner.

A further object of the invention resides in the provision of a relatively inexpensive, accurate and positive compensating wind-up mechanism in which the compensating means are controlled directly by the wound or unwound material.

It is also an object of the invention to provide means for mounting the reeling means and the slip sheet or liner roll so that the roll changes can be quickly and easily made.

The above and other objects of the invention are achieved by the apparatus illustrated in the accompanying drawings and described below, it being understood that the invention is not limited to the exact details shown and described.

In the drawings:

Figure 1 is a side elevation of the apparatus embodying the invention;

Figure 2 is a plan view of the apparatus shown in Figure 1;

Figure 3 is a sectional view taken on line 3—3 of Figure 2;

Figure 4 is a sectional view taken on line 4—4 of Figure 1;

Figure 5 is a sectional view taken on line 5—5 of Figure 4;

Figure 6 is a sectional view taken on line 6—6 of Figure 4; and

Figure 7 is an enlarged view taken on line 7—7 of Figure 2, but with parts in inoperative position.

The invention is particularly adapted for use with continuously printed webs of regenerated cellulose, known in the trades as "Cellophane", and has, therefore, been described in conjunction therewith. The "cellophane" presents a smooth, non-absorbing surface and when continuously passed, in web form, thru a roll printing press, special handling is necessitated to prevent the offsetting or smearing of the printed matter. It has been found that certain materials, which will hereafter be called slip sheet,

will, if wound up between the convolutions of the "cellophane", prevent offsetting.

Referring to the drawings, the numeral 11 indicates a frame upon which is mounted a slip sheet roll 14 by any suitable means, which may include a pair of open pillow blocks 12 which serve to journal a shaft 13. Removably carried on the shaft 13 is the roll of slip sheet 14, which is wound up on a cardboard or similar core 15. The core 15 of the roll is centered and secured to the shaft 13 by suitable means, such as flanged hubs 16 and 17. One of the hubs is fixed as at 17a to the shaft 13, and the other may be feathered to a wide collar 18, which is removably secured to the shaft 13 by a set screw 19. The collar 18 is threaded and provided with a nut 21, which can be run down against the hub to clamp the core 15 securely between the flanged hubs 16 and 17.

A tension must be applied to the slip sheet roll so that the slip sheet 14 will be properly and smoothly fed without any tendency to overrun. To this end a stud pin 22 may be fixed to the frame 11 which will serve to pivotally support a pair of curved brake shoes 23 and 24, which are provided with any suitable friction means 25 that bear against a drum 26 secured to the shaft 13. In the embodiment of the invention shown, the drum 26 is grooved and the friction means are correspondingly wedge-shaped, which serves to prevent end play of the shaft 13. The end of the shoe 24 is curved back and bifurcated as at 27 to pivotally receive a bell lever 28. The short arm of the bell lever 28 makes a slot and pin connection 29 with a rod 31 which extends thru the shoe 27. The end of the shoe 23 is also bifurcated to receive a bolt 32, which is pivotally secured to the end of the rod 31. A spring 33 and adjusting nuts 34 are preferably provided on the bolt 32 which, together with the position of the bell lever 28, will control the frictional effect of the brake.

In order to reduce the force of the brake, as the roll of slip sheet 14 diminishes in diameter, brackets 35 may be provided on the sides of the frame 11 to journal a shaft 36. The angular position of the shaft 36 is controlled directly by the size of the slip sheet roll by providing a pair of arms 37 which are fixed to the shaft 36, and which journal a shaft 38 upon which is mounted a rubber roller 39 that rides directly on the slip sheet roll as shown. The shaft 36 is extended on the brake side of the frame and is provided with a crank arm 41, which crank arm 110

is connected by an adjustable link 42 with the long end of the bell lever 28.

From the slip sheet roll the slip sheet 14 is preferably passed under a roller 43, which may be journaled in the brackets 35, and thence to the wind-up roll. The wind-up roll, in the form of the invention illustrated, includes a transversely split shaft comprising members 44 and 45. The shaft member 44 is formed with an enlarged socket 46 at its inner end, which is adapted to removably receive a reduced squared end 47 of the shaft 45. The squared end 47 of the shaft is not inserted endwise in the socket 46, but is preferably moved in from the side, the socket being grooved as at 48 for this purpose. To hold the squared end 47 of the shaft in the socket, a collar 49 may be slidably carried on the socket 46 to which collar is secured a block 51, which slides in the groove 48 as shown in Figures 4 and 6. The extent of outward movement of the collar 49 may be limited by a pin and slot connection 52 and the collar may be releasably held in its outermost position by a spring detent 53.

The shaft 44 is journaled in a bearing 54 secured to the frame 11, and is adapted to be rotated thru a gear 55 secured to the shaft by any suitable means (not shown).

The shaft 45 is journaled in a pillow 56 secured to the frame 11, which pillow may be provided with a hinged cap 57 which is adapted to be removably clamped against the pillow by means of a pivotally mounted bolt 58 having a wing nut 59. The bolt 58 is received in a suitable slot in the hinged cap, as will be understood.

The freshly printed web "cellophane" is indicated by the numeral 61, and is adapted to be continuously passed from the printing means (not shown) over an idler roller 62 to the wind-up mechanism. The "cellophane" web 61 and the slip sheet 14 are wound together upon a cardboard or other suitable core 63, which is removably held on the shaft 45 by suitable means, including flanged hubs 64 and 65. The flanged hub 64 is feathered to the shaft 45, and is removably held thereon by a nut 66 which cooperates with a threaded portion of the shaft 45 which, from the thread out to the end of the shaft, is reduced in diameter for this purpose, as indicated in Figure 3. The flanged hub 64 is preferably adapted to be tightened up against a collar 67 or other similar means secured to the shaft 45.

The flanged hub 65 is also feathered to the shaft 45, and may be limited in its inward movement by a collar 68, which collar is, however, so positioned as to be spaced from the hub during the operation of the apparatus. A collar 71 is secured to the shaft 45 adjacent the socket 46. Mounted on the shaft 45, between the collar 71 and the hub 65, is a yoke 72, having diametrically-opposite flattened sides 73. Journaled in suitable blocks 74 secured to the flattened sides 73 of the yoke 72 are rollers 75. Thrust bearings 76 and 77 are preferably mounted on the shaft 45 at each side of the yoke 72 so that thrust bearing 76 lies between the collar 71 and the yoke 72. The other thrust bearing 77 lies between the yoke 72 and a collar 78 which is slidably mounted on the shaft 45. A spring 79 is held between the collar 78 and the flanged hub 65.

Cooperating with the yoke 72 is a wedge fork 81, which is formed with parallel inner sides 82

that make a sliding fit with the flat sides 73 of the yoke. The wedge faces of the fork are indicated at 83, and are adapted to engage with the rollers 75. As illustrated in Figure 4, the roller journaling blocks 74 are cut away parallel to the faces 83 of the wedge fork 81.

The fork 81 may be slidably mounted on a rod 84 which is connected, preferably thru a turnbuckle 85, to an arm 86, secured to the shaft 36. In order to allow the wedge fork 81 to be moved out of the way, so that the axle 45 with the tube 63 can be removed from the apparatus, suitable means are provided which may include a collar 87, which is secured to the rod 84. The fork 81 can be connected by toggle linkage 88-89 with the collar 87, a handle 91 being provided on the toggle for operating purposes. The operative and inoperative positions of the fork 81 are shown in Figures 1 and 7 respectively.

In order to keep the following roller 39 in the inoperative dotted position shown in Figure 1, an arm 92 is secured to the shaft 36 to which arm is pivotally fastened a rod 93, which rod is adapted to be moved, as shown in dotted lines, over to rest on a shelf 94 secured to the frame 11, thus holding the roller 39 in its inoperative position. When the roller 39 is in operating position the rod 93 hangs from the arm 92.

The operation of the device is as follows:

Assuming the shaft 13 has been removed from the apparatus, the set screw 19 of the collar 18 is loosened and the collar 18, nut 21 and flanged hub 16 are removed from the shaft 13. A roll of slip sheet 14 wound on a tube 15, is now slipped over the shaft 13 and down against the flanged hub 17. The collar 18, nut 21 and flanged hub 16 can now be slipped over the shaft 13 and down against the tube 15, whereupon the set screw 19 is tightened, and the nut 21 is thereafter run down to tightly clamp the tube 15 of the slip sheet roll between the flanges 16 and 17.

With the roller 39, bolt 32 and brake shoe 23 in their dotted positions as shown in Figure 1, the shaft 13 with the slip sheet roll mounted thereon, is laid in the pillows 12 on the frame 11, whereupon the brake shoe 23 can be swung up to its full line position and held thereat by the bolt 32, which is swung down and over the bifurcated end of the shoe 23, as shown in full lines in Figure 1. The means journaling the roller 39 is now raised and the rod 93 falls away from the shelf 94 so that the roller 39 can be lowered down on top of the slip sheet roll.

Assuming the windup shaft 45 has been removed from the apparatus, the nut 66 and flanged hub 64 are removed from the shaft 45 and a tube 63 is placed thereon, after which the flanged hub and nut are returned to the shaft and the nut 66 run down to clamp the hub 64 against the collar 67. The shaft 45 is now returned to the frame 11, the collar 49 on the socket 46 being in the retarded dotted position shown in Figure 4 during this operation. The square end 47 of the shaft 45 can thus slide into the end of the socket 46 thru the opening 48, after which the collar is moved back to its full line position so that the opening 48 is closed by the block 51 secured to the collar 49. The spring detent 53 removably holds the collar in its locking position. The other end of the shaft 45 is received in the pillow 56, and

the cap 57 is thrown down and bolted in place by the hinged bolt 58 and wing nut 59.

The handle 91 is operated to straighten out the toggle linkage 88 and 89, thus moving the wedge fork 81 down into cooperating relation with the yoke 72. It is necessary that the yoke 72 be turned exactly right so that the flat parallel inner sides 82 will slide over the flat sides 73 of the yoke. The slip sheet 14 is now brought by hand under the roller 43, and is wrapped about the tube 63, and the "cellophane" 61 is brought from the printing apparatus to and around the tube 63 between the convolutions of the slip sheet.

14 The apparatus is now ready to start operation, so the printing mechanism is started and the wind-up is driven thru the gear 55 by any suitable means, but preferably from the printing mechanism. The wind-up shaft 45 is over driven, that is, it is driven so that the tube 63 would have a greater surface speed than that at which the "cellophane" 61 is supplied from the printing mechanism. There is thus slippage between the flanged hubs 64 and 65 and the tube 25 63. As the wind-up tube 63 revolves it will, of course, pull the slip sheet 14 and revolve the slip sheet roll and shaft 13 against the action of the brake 23-24.

As the slip sheet roll diminishes in size and the wind-up roll begins to build up, the roller 39 will follow the slip sheet roll, thus turning the shaft 36. As the shaft 36 slowly turns, the tension of the brake 23-24 on the slip sheet roll will gradually diminish, because the bell crank 35 28 is rocked thru link 42 and arm 41, to bring the slot and pin connection 29, between the rod 31 and the short arm of the bell crank 28, nearer the opposite shoe 23. At the same time the frictional drive between the wind-up tube 63 and flanged hubs 64 and 65 is increased, inasmuch as the wedge fork 81 is moved inwardly by the slow turning of the shaft 36, thru the agency of the arm 86, turnbuckle 85 and rod 84. As the fork 81 moves inwardly, the wedge 40 45 surfaces 83 contact with the rollers 75, which will force the yoke 72 in towards the flanged hub 65, thus increasing the compression on the spring 79. This in turn forces the hub 65 over against the tube 63 with greater force to increase the frictional drive. The thrust bearings 76 and 77 allow this operation to take place without interfering with the turning of the wind-up.

When the wind-up is completed for the roll 55 of slip sheet employed, the printing mechanism and the wind-up drive are stopped. The bolt 32 is swung up to the dotted position shown in Figure 1 to disengage from the bifurcated end of the brake shoe 23, which can then be dropped 60 down as shown by dotted lines in the same figure. The roller 39 is lifted and the rod 93 is swung over so that its lower end rests on the shelf 94, thus holding the roller 39 and its supporting mechanism in the dotted inoperative position shown in Figure 1. The wedge fork 81 is drawn back out of the way by breaking the toggle 65 70 88-89 thru operating handle 91.

The axle 13 can now be lifted from the pillows 12, and a new slip sheet roll mounted thereon as described above.

The woundup roll is removed from the frame by pressing the spring detent 53, and sliding the collar 49 back to the dotted position shown in Figure 4. The operator should take care that the opening 48 in the socket 46 is somewhere

near the top when the apparatus stops, so that the squared end 47 and thus the shaft 45 does not fall when the collar 49 is slid back. The wing nut 59 is loosened, and the bolt 58 is dropped back so that the cap 57 can be thrown back. The shaft 45 with the rolled material thereon can now be lifted out, and the roll removed from the shaft by removing the nut 66 and hub 64. A new tube 63 is then mounted on the shaft 45, and the unit is replaced on the apparatus as described above, whereupon the entire operation can be repeated.

It will be seen that the initial tension upon the slip sheet roll can be controlled by adjusting the nuts 34 on the bolt 32, and by adjusting the length of the link 42. In a like manner by adjusting the turnbuckle 85, the frictional force of the wind-up drive can be initially controlled. These adjustments can also be made while the mechanism is in operation, but the parts have been designed so that except in extreme cases, this is not necessary inasmuch as the automatic mechanism will take care of all compensating adjustments.

While the compensating features of the invention have been particularly described in combination with a wind-up mechanism wherein a slip sheet or liner is inserted between the convolutions of a wound-up web material, it will be seen that the compensating mechanism 105 can be employed either in winding or unwinding a single web of material. In case of unwinding, the braking means and the compensating means shown therefor can be used. In winding operations, the following roller 39 with 110 its mounting means need only be turned around to rest on the material being wound up.

Moreover it will be evident that while the invention has been described for use with freshly printed "cellophane" and slip sheet, that it can 115 readily handle any web material and any liner.

It will be understood that in accordance with the patent statutes, a specific embodiment only, of the invention has been described, and that the scope of the invention is defined in the appended claims.

What is claimed is:

1. Apparatus for winding up web material with liner between the convolutions thereof, including a wind-up shaft, means for journaling and rotating said shaft, means removably mounted on said shaft and having a frictional drive therewith upon which means the web material is wound, a liner roll, means rotatably and removably mounting said roll, braking means on said liner roll, and means for reducing the force of the braking means and for simultaneously increasing the frictional drive between the shaft and the means upon which the web material is wound.

2. Apparatus for winding up web material with liner between the convolutions thereof, including means upon which the web material is wound, means for rotating said first named means, a frictional drive between said first named means and said rotating means, a liner roll, braking means on said liner roll, and means for increasing the frictional force of friction drive and for simultaneously reducing the force of the braking means.

3. Apparatus for winding up web material with liner between the convolutions thereof, including means upon which the web material is wound, means for rotating said first named means, a frictional drive between said first

- named means and said rotating means, a liner roll, braking means on said liner roll, and means for increasing the frictional force of friction drive and for simultaneously reducing the force of the braking means, said last-named means being automatically controlled by the diameter of the liner roll. 80
4. Apparatus for winding up web material with liner between the convolutions thereof, including means upon which the web material is wound, means for rotating said first named means, a frictional drive between said first named means and said rotating means, a liner roll, braking means on said liner roll, and means for increasing the frictional force of friction drive and for simultaneously reducing the force of the braking means, said last-named means being automatically controlled in direct proportion to the amount of web material wrapped on the first named means. 85
5. Apparatus for winding up web material with liner between the convolutions thereof, including means upon which the web material is wound, means for rotating said first named means, a frictional drive between said first named means and said rotating means, means for supplying liner, braking means on said liner supply, and means for increasing the frictional force of friction drive and for simultaneously reducing the force of the braking means. 90
6. Apparatus for winding up material with liner between the convolutions thereof, including means upon which the material is wound, means for rotating said first named means, a frictional drive between said first named means and said rotating means, a liner roll, braking means on said liner roll, and means for increasing the frictional force of friction drive and for simultaneously reducing the force of the braking means. 95
7. In an apparatus of the class described, means upon which material may be rolled, said means including a journaled shaft, a removably fixed, flanged hub on said shaft, an oppositely facing flanged hub feathered on said shaft spaced from said first-named flanged hub, a tube carried between said hubs and frictionally driven thereby, means for rotating said shaft, a yoke rotatably mounted on said shaft, spring means between said yoke and said feathered hub, wedge means for moving the yoke towards the flanged hub to increase the frictional drive between the hubs and the tube, and means for automatically operating said wedge means in proportion to the material wound on said material receiving means. 100
8. In apparatus of the class described, means upon which material may be rolled, said means including a journaled shaft, a removably fixed, flanged hub on said shaft, an oppositely facing flanged hub feathered on said shaft spaced from said first-named flanged hub, a tube carried between said hubs and frictionally driven thereby, means for rotating said shaft, a yoke rotatably mounted on said shaft, spring means between said yoke and said feathered hub, and wedge means for moving the yoke towards the flanged hub to increase the frictional drive between the hubs and the tube. 105
9. In apparatus of the class described, means upon which material may be rolled, said means including a journaled shaft, a fixed, flanged hub on said shaft spaced from said first-named flanged hub, a tube carried between said hubs and frictionally driven thereby, means for rotating said shaft, a yoke mounted on said shaft, spring means between said yoke and said feathered hub, and means for moving the yoke towards the flanged hub to increase the frictional drive between the hubs and the tube. 110
10. In apparatus of the class described, means upon which material may be rolled, said means including a journaled shaft, a fixed, flanged hub on said shaft, an oppositely facing flanged hub feathered on said shaft spaced from said first-named flanged hub, a tube carried between said hubs and frictionally driven thereby, means for rotating said shaft, a yoke mounted on said shaft, radially journaled rollers on said yoke, spring means between said yoke and said feathered hub, wedge means for moving the yoke towards the flanged hub to increase the frictional drive between the hubs and the tube, said wedge means and yoke having a sliding, non-rotative fit. 115
11. In apparatus for winding and unwinding web material, means upon which the web material is rolled, said means including a transversely split shaft, one portion of said shaft being relatively short and formed with a socket at its inner end, the other portion of said shaft being relatively long, a tube upon which the web material is actually wound, said tube being removably supported on the long portion of the shaft, said long portion being formed at its inner end to fit in the socket on said short portion, means for removably holding said long and short portions of said shaft together, means for non-removably journaling said short portion substantially throughout its length, and means for removably journaling said long portion at the outside of the tube. 120
12. In apparatus for winding and unwinding web material, means upon which the web material is rolled, said means including a transversely split shaft, one portion of said shaft being relatively short, the other portion of said shaft being relatively long, a tube upon which the web material is actually wound, said tube being removably supported on the long portion of the shaft, means for removably holding said long and short portions of said shaft together, means for journaling said short portion substantially throughout its length, and means for removably journaling said long portion at the outside of the tube. 125
13. In apparatus of the class described, means supporting a roll of web material, a brake drum on said roll supporting means, a pair of brake shoes pivotally supported in cooperating relation with said drum, an auxiliary shaft, a follower fixed to said auxiliary shaft and adapted to ride on the periphery of the roll of web material, a bell lever pivoted at its elbow on the end of one of said brake shoes, means connecting one arm of the bell lever with the end of the other brake shoe, a crank arm on the auxiliary shaft, and means connecting the crank arm with the other arm of the bell lever whereby a reduction or increase in diameter of the rolled web will respectively decrease or increase the tension of the brake. 130
- KARL E. ANDERSON. 135
